UNITED STATES PATENT OFFICE.

MARTIN M. HEISLER AND AUGUST G. WITTE, OF CHICAGO, ILLINOIS.

LUBRICATOR.

1,109,125.

Specification of Letters Patent.

Patented Sept. 1, 1914.

Application filed June 19, 1913. Serial No. 774,550.

To all whom it may concern:

Be it known that we, MARTIN M. HEISLER and AUGUST G. WITTE, citizens of the United States, and residents of the city of Chicago, county of Cook, and State of Illinois, have invented certain new and useful Improvements in Lubricators, of which the following is a specification.

Our invention relates to improvements in lubricators especially adapted for use on elevators, and has for its object the provision of an improved device of this character which is of simple construction and efficient in operation.

The invention consists in the combinations and arrangements of parts hereinafter described and claimed.

The invention will be best understood by reference to the accompanying drawing forming a part of this specification, and in which,

Figure 1 is a side view shown partially in section of a lubricator embodying the invention, and shown in position of use, Fig. 2 is an enlarged vertical section of said lubricator, Fig. 3 is a top plan view of the lubricator with the cover removed, and Fig. 4 is a partial section taken on line $x-x$ of Fig. 3.

The preferred form of construction as illustrated in the drawing comprises an oil receptacle 1 which is made substantially U-shaped in horizontal section so as to provide a recess 2 adapted to receive the ordinary guide rail 3 of an elevator construction. The receptacle 1 is provided at its back with a socket 4 and a set screw 5 by means of which it may be secured to a rod or pin 6 secured on the elevator car in any usual or desired manner.

The walls of receptacle 1 surrounding recess 2 are extended upwardly at their upper ends 7 somewhat beyond the remaining walls of said receptacle and each of these upwardly extending wall portions is provided with a slot or opening 8 adapted to permit the passage of a wick 9 therethrough. Each of the wicks 9 is preferably folded as indicated in Figs. 2 and 3. Set screws 10 are passed downwardly through wall portions 7 in position to engage the protruding ends of wicks 9 and thus serve as means for anchoring said wicks in position and also adjusting said wicks so that the ends thereof will contact with the sides of guide rail 3 to supply oil thereto. Re-

ceptacle 1 is provided with an upwardly swinging cover 11 which has the same general shape as said receptacle and is mounted to swing upon a pivot pin 12 at the rear of the receptacle. Pivot pin 12 carries springs 13 and 14 arranged to hold said cover normally in closed position.

In use the receptacle 1 is supplied with a suitable quantity of oil and the wicks 9 adjusted so that their ends will contact with guide rail 3. Thus when the car is in motion there is a certain frictional or suctional action on the oil in the wick which tends to induce feeding of said oil and to assist the capillary attraction of the wick to supply oil to the guide rail 3. Thus the wick will only feed oil during motion of the car and consequently will not drip oil when the car is stationary or not in use. The action of the lubricator is entirely noiseless and no springs or delicate parts are employed which might readily become out of order. The wicks are rendered adjustable to insure proper action thereof and to compensate for any wear and the spring held cover will exclude all dust and grit from the oil chamber. It will also be observed that in the construction set forth there are no exposed or open parts to accumulate dust and grit.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having described our invention what we claim as new and desire to secure by Letters Patent is:

1. A lubricator comprising an oil receptacle having a recess therein adapted to receive a guide rail, there being openings through the walls of said receptacle; and wicks suspended in the receptacle with their ends protruding through said openings and adapted to contact endwise with a guide rail in said recess, substantially as described.

2. A lubricator comprising an oil receptacle having a recess therein adapted to receive a guide rail, there being openings through the walls of said receptacle; a spring held cover for said receptacle; and

wicks suspended in the receptacle with their ends protruding through said openings, substantially as described.

3. A lubricator comprising an oil receptacle having a recess therein adapted to receive a guide rail, there being openings through the walls of said receptacle; wicks suspended in the receptacle with their ends protruding through said openings; and screws securing the upper ends of said wicks in said openings, substantially as described.

4. A lubricator comprising an oil receptacle having a recess therein adapted to receive a guide rail, there being openings through the walls of said receptacle leading

into the upper portion of said recess; a spring held cover for said receptacle; wicks suspended in the receptacle with their ends protruding through said openings; and screws securing the upper ends of said wicks in said openings, substantially as described.

In testimony whereof we have signed our names to this specification in the presence of two subscribing witnesses.

MARTIN M. HEISLER.
AUGUST G. WITTE.
